SYRINGE ASSEMBLY

George N. Hein, Jr., San Carlos, Calif.

Application December 19, 1952, Serial No. 326,907

19 Claims. (Cl. 128—218)

This invention relates to a structurally and functionally improved syringe assembly of the hypodermic type.

In its more specific aspects, it is a primary object to provide an assembly of the disposable type and which will operate in an extremely desirable manner; the assembly being discardable after it has once been used.

A further object is that of furnishing an assembly of this character which will include relatively few parts each individually rugged and simple in construction, such parts being largely capable of manufacture by automatic machinery and being moreover capable of ready assembly, sterilizing and filling to furnish an apparatus which may be quickly and efficiently operated even by a relatively unskilled user.

With these and other objects in mind, reference is had to the attached sheets of drawings illustrating practical embodiments of the invention and in which:

Fig. 1 is a sectional side view of an assembly in its initial condition;

Fig. 2 is a similar view with the parts adjusted or shifted so that an injection may be achieved;

Fig. 3 is a fragmentary sectional view similar to Fig. 1 but showing an alternative form of structure;

Fig. 4 is a transverse sectional view taken along the line 4—4 in the direction of the arrows as indicated in Fig. 3;

Fig. 5 again shows a view similar to Fig. 1 but illustrating a further form of assembly;

Fig. 6 is a sectional side view of an assembly similar to Fig. 1 and showing the same in position within a holder;

Fig. 7 is a view corresponding to Fig. 6 but showing the parts in partially discharged positions;

Fig. 8 shows the present invention combined with a multi-compartment ampule structure;

Fig. 9 is a sectional side view of a still further form of assembly;

Fig. 10 is a view similar to Fig. 9 but showing the position which the parts assume at substantially the completion of the injection;

Fig. 11 shows in sectional side elevation a still further form of assembly; and

Fig. 12 is a sectional side view of a rear portion of a cannula and showing an actuating wire or member attached thereto.

Referring primarily to Figs. 1 and 2, the numeral 15 indicates a barrel or tube preferably formed of glass and which in this embodiment is open at both ends. A wall in the form of a headed stopper including a plug portion 16 closes one end of the barrel or ampule. This stopper is formed with a recess 17 in its inner face which terminates short of the outer face of the head portion. Consequently, a pierceable diaphragm area exists between these parts; the stopper being formed of a material such as rubber. The outer end of recess 17 is conveniently enlarged as at 18. A needle 19 has its pointed outer end extending into recess 17 and lying adjacent the diaphragm

2

portion. A wire 20 extends through the body of the stopper and has its rear end secured to the inner end portion of needle 19 which is conveniently offset or bent so as to assure an anchoring of the parts as indicated at 21. The outer end of the wire or member 20 may terminate in a loop 22 or other suitable actuating portion.

The sterility of the outer face of the stopper through the area pierced by the needle 19 may be maintained by a tab 23. The latter is capable of ready removal from this surface. The rear end of the tube or barrel 15 is conveniently closed by stopper 24 of the piston type. A convenient form of coupling is provided by a stem 25 which may extend from the rear face of this stopper and be capable of being connected to an actuator 26 so that it will be susceptible to both projection and retraction. The interior of the ampule or barrel is filled with liquid 27 to be injected.

It will be assumed that the several parts have been cleaned and assembled and that the interior of the ampule 15 has been filled with the desired solution. If now, an injection is to occur, all that an operator will have to do will be to grasp the outer end 22 of the actuating member 20 and to exert a pull thereon. Prior to this, tab 23 will have been removed. Due to the coupling between member 20 and needle 19, a pulling action will cause the needle to be projected until it assumes the position shown in Fig. 2. During this projection, care should be employed to prevent a dislodgement of stopper 16. Of course, the latter may be manufactured to be secured in one of a different number of manners to tube 15 so that it may not be displaced with respect thereto. When the needle is fully projected, wire 20 may be bent to extend over and around the stopper and back along the outer face of the ampule body 15. So disposed, the needle will be held quite firmly and accordingly, the device may be used as a syringe by simply projecting the barrel and the associated parts towards the epidermis so that the pointed end of the needle will pierce the same and lodge within the underlying tissues. If now by means of plunger 26, piston 24 is projected, medicament 27 will be discharged through the bore of the cannula and an injection will thus be completed. If a coupling of the nature suggested is employed between actuator 26 and stem portion 25 of the piston, then the latter may be retracted so that an aspirating action may be resorted to.

Under certain conditions it may be desirable to have the wire or equivalent member bear in sliding engagement with the interior smooth surface of ampule 15 and to provide an offset needle and rigid guide. This has been shown in Figs. 3 and 4 in which the needle and its wire have been disposed eccentrically with respect to the stopper 28; it being apparent that it is desirable not to have the axes of these elements separated to too great an extent. Therefore, the recess 29 in the stopper is disposed in off-center position. The groove accommodating the wire should have an initial cross-sectional area less than that of the wire so that a firm sealing contact is established which will prevent any leakage. Of course, in all instances, it is preferred that the diameter of the stopper plug be initially greater than that of the bore of the barrel which receives it so that a firm sealing fit is established between these parts. In any event, it will be apparent that the operation of the assembly as shown in Figs. 3 and 4 will be identical with that heretofore described with respect to Figs. 1 and 2.

Referring to Fig. 5 there has been shown a container which, instead of being manufactured of glass or similar material as in the instance of the container or tube 15, is formed of a flexible material. This container has been indicated at 30 and is preferably manufactured of a plastic such as polyethylene. Its rear end is convenient-

ly closed by an integral wall portion and its forward end may be defined by an outwardly extending bead 31. A stopper 32 seals the forward end of the container and is formed of rubber or similar material and with a bore into which the piercing end of the needle 19 extends. The stopper may additionally include a rearwardly extending flange portion 33 which overlaps the bead 31 and interlocks with the container so that there will be no danger of the stopper being accidentally displaced from sealing relationship with respect to the body of the ampule or tube 30. Instead of off-setting the rear end of the cannula 19 and wrapping the adjacent end of wire 20 around the same, spot welding as at 34 may be resorted to to connect these parts.

A limited degree of aspiration is possible in this assembly by properly manipulating the parts. In any event, a person desiring to perform an injection will initially strip the protecting tab 23 or its equivalent from the stopper. Thereafter by exerting a pull upon wire or rod 20, needle 19 is caused to perforate the diaphragm portion of the stopper and be projected beyond the same to its full effective length. In common with the previously described structure, the projected position will be defined by the stopper bore surfaces adequately engaging the exterior face of the cannula so as to support the same. Moreover, the offset rear end portion of the member 20 will preferably lie in contact with the rear face of the stopper and will serve as a brace to anchor the cannula against any substantial movement with respect to the stopper. The latter being in turn anchored against movement with respect to the container 30, it follows that the entire assembly may be regarded as effectively rigid when the needle is in projected position. Any accidental retraction of the parts is precluded by extending the wire 20 rearwardly in a manner similar to that shown in Fig. 2 after needle projection has occurred. The site of injection having been chosen, it follows that the outer end of the needle may be plunged through the epidermis at this point and after it has penetrated the tissues to the desired depth, the operator may squeeze container 30 so as to collapse the same. Under this action of the parts, the medicament 27 will be expressed through the bore of the cannula and thus the desired hypodermic injection will be effected.

In certain instances, it may be desired to employ an assembly of the type shown, for example, in Figs. 1 to 4 inclusive in a holder. The assembly will, under these circumstances, also have a "one-time use." The holder will be used repeatedly and have an indefinite life. With this thought in mind, attention is directed to Figs. 6 and 7 which illustrate one form of combination which may conveniently be employed. In those views, the numerals 15, 19, 20 and 22 are to be regarded as designating the parts of an assembly substantially corresponding to similar parts as heretofore described and shown. A holder will preferably include a base or rear portion defined by an outwardly extending flange 35 for convenient engagement by the fingers of an operator. Extending forwardly of this flange will be a tubular part 36 which is formed with side openings adequate in width to receive the ampule or tube 15. These openings will also be of a length such that the tube may readily be inserted and removed therethrough. The forward end of the holder is conveniently defined by an inwardly extending flange portion 37. This engages with the outer face of the forward stopper 38 of the ampule; such stopper serving to cushion the contact between the assembly and the holder. Moreover, as will be seen the stopper will be prevented from being outwardly displaced by this annular flange portion.

The holder will present to the rear of flange 35 a collar portion 39 which slidably receives an assembly including a rod 40 having its forward end terminating in a substantially spherical projection 41. The latter may be received by the socket or cup portion 42 formed in the rear face of piston stopper 43. Rod 40 is conveniently

formed with a longitudinally extending groove 44 into which the end of a pin 45 carried by collar 39 extends. Therefore, rod 40 is prevented from rotating with respect to that collar. A sleeve 46 slidably encircles rod 40 and has direct bearing engagement with the bore of collar 39. This sleeve preferably terminates in a rear flanged part 48 at a point short of the rear end of rod 40. A spring 49 bears against this part as well as against an actuator portion 50 secured to the rear end of the rod. Finally, with respect to this assembly, it will be noted that the tubular portion of the holder preferably provides a notch or rearwardly extending hook portion 51.

In using an apparatus of this nature, it will be understood that the ampule is dropped through one of the side openings 36 of the tubular holder while the plunger parts are maintained in the position shown in Fig. 6. At that time or else after the needle is shifted to projected position, plunger 40 is moved so that its spherical or otherwise curved outer end portion enters cup or socket 42. During this operation, sleeve 46 may be maintained in relatively retracted position by exerting a restraining action on flange 48. Whether this is done or not, however, the forward flared edge portion 47 of the sleeve will eventually bear upon the flexible lip of cup 42 and cause it to be clamped against the rear or diminishing face of portion 41. Under these circumstances, stopper 43 will be secured against movement with respect to rod 40 and whether the latter is projected or retracted.

Assuming that it has not previously been done, needle 19 is now projected by exerting a pull on wire 20 in an outward direction. This will shift the needle to the position shown in Fig. 7. In order to lock the parts and also to secure the end of wire 20 in a position at which it will not interfere with subsequent operations, the latter may be passed through the notch or hook portion 51 as also shown in this figure. If now the assembly is projected towards the epidermis, needle 19 will pierce the latter and lodge within underlying tissues to the desired depth. Thereafter, if pressure is brought to bear against actuator 50, rod 40 will project to correspondingly project piston 43 and eject medicament through the bore of the cannula. As is apparent, due to the coupling existing between this piston stopper and the rod, aspiration may be resorted to so that a physician or other attendant will be able to determine whether the outer end of the needle is lodged within a vein or not. After injection has been completed, the rod assembly will be retracted and sleeve 46 will be shifted rearwardly so as to release the portions of the cup 42 which are adjacent its lip. Now, with retraction of the needle and by inserting the finger or any suitable instrument through one of the openings 36, the ampule assembly may have its rear end dislodged. Therefore, it may be withdrawn and discarded.

As heretofore described, the rear end of wire 20 may be simply coiled around the rear end of the needle in which case the latter is preferably offset; all as indicated at 21. Also, as at 34, the rear end of this wire may be spot welded to the outer face of the cannula. As shown especially in Fig. 12, the rear end of the wire 20 may be turned upon itself as at 52 to pass over the rear edge of cannula 19 and extend axially of the same. The hooked rear portion of the wire is conveniently spot welded in this case as at 53. Such an arrangement of parts has generally been resorted to in the structures as shown in Figs. 6 and 7 as well as in Figs. 9, 10, and 11 hereinafter described.

A different arrangement of securing the rod to the cannula has been shown in Fig. 8 in which the wire 54 is, for example, spot welded as at 55 to the outer face of the cannula and is continued beyond the same. The primary purpose of this structure is that of providing a multi-compartment ampule in which diluent may be initially stored in one compartment and medicament in the other. To this end, the compartments are defined to opposite sides of a stopper 56 which serves as a partition inter-

mediate the ends of tube 15. This stopper is formed with a central opening or bore, normally sealed by a sphere 57 or other suitably shaped body having a diameter greater than that of the bore so as to establish firm contact with the surfaces defining the latter. In this view, the diluent has been indicated at 53 and the medicament at 59.

If a unit of this type is to be employed in connection with a holder of the general character shown in Figs. 6 and 7, then a piston-type stopper such as 43 having a cup or recess portion 42 may be employed. Otherwise, a stopper such as is shown in Figs. 1 and 2 may be utilized. In any event, assuming that the assembly is ready for use, it is apparent that a pull upon wire 54 will result not alone in a piercing of the forward stopper by the cannula but will also result in sealing element 57 being dislodged from the stopper 56. Therefore, the diluent 58 may flow through the bore into contact with the medicament 59. The parts may be agitated or otherwise manipulated so as to assure of the establishment of a proper solution. Thereafter, piston stopper 43 is projected to force the solution through the bore of stopper 56. With the assembly held in a vertical position, all air will be vented through the bore of the cannula. Finally, stopper 43 will bear against stopper 56. When this position of the parts has been established, or, in any event, when all air has been vented, perforation of the epidermis may be resorted to. Thereafter, by projecting stoppers 43 and 56, the solution will be forced through the bore of cannula 19 and thus the desired hypodermic injection will be achieved. As will be observed in Fig. 8, the rear face of the stopper is formed with a recess 60 of adequate area to not alone accommodate the rear ends of the cannula and wire 54 adjacent their point of juncture but also to receive the sealing element 57.

In certain instances it may be desired to provide a syringe in which no rearwardly extending plunger or actuator is present. Such a structure has been shown in Figs. 9 and 10. Additionally, there has been shown in these views a bead or member 61 which, similarly to the sealing element 57, may be fused onto the wire 20. In this case, it will, of course, serve as an actuating element enabling the wire to be readily pulled to project the needle. A stopper 62 seals the forward end of the ampule in Figs. 9 and 10 and is provided with an outwardly extending flange portion 63. A piston stopper 64 closes the rear end of the ampule and may have a washer or plate 65 disposed adjacent it. A wire or rod 66 has its rear end secured against displacement with respect to this plate and thereafter conveniently extends through the stopper 64. This wire also extends through stopper 62 and preferably at a tangent to the axis of the same. Again, its outer end may mount a spherical pull element 67.

In using an assembly of this nature, wire 20 is pulled to project needle 19. With the site of injection having been chosen and the wire having been folded back around stopper 62, the needle will be locked against displacement. The needle may now be plunged through the epidermis into the tissues as in Fig. 10. Now, if a pull is exerted upon wire 66, piston stopper 64 will project. Therefore, the solution within the ampule will be forced through the bore of the cannula into the tissues or vein. As will be understood, the parts may operate in this manner without difficulty because, as indicated in Fig. 10, a pull on wire 66 in a lateral direction will still transmit adequate force to piston stopper 64 due to the preferably eccentric disposition of needle 19. Therefore, with the needle to one side of the center zone of the stopper and wire 66 upon the opposite side, no difficulty will be experienced in properly piercing the tissues to the desired depth while at the same time having sufficient space to assure a projection of the stopper 64.

An apparatus such as in Figs. 9 and 10 will, of course, not permit of aspiration. However, the structure may be modified so that this result will obtain. Thus, as

in Fig. 11, wire 66 may be continued materially beyond stopper 64 and have at its rear end a second actuating or spherical element 68. In addition to plate 65 a forward plate 69 may be disposed adjacent piston 64 and wire 66 secured so as to shift stopper 64 in either direction according to whether a pull is exerted on element 67 or 68. The procedure with respect to the parts will be precisely the same as heretofore described in connection with Figs. 9 and 10. Additionally, however, after penetration of the tissues has once been effected, an operator may, by pulling upon element 68, retract stopper 64. This results in an aspirating action. Thereafter, by pulling on element 67, injection will occur.

Thus, it is apparent that among others the several objects of the invention as specifically afore noted are achieved. Obviously numerous changes in construction and rearrangements of the parts may be resorted to without departing from the spirit of the invention as defined by the claims:

I claim:

1. In a syringe assembly in combination a medicament container, a wall closing one end of said container, a hollow needle within said container and having its outer pointed end disposed adjacent said wall and means extending forwardly of said wall for projecting said needle therethrough.
2. In a syringe assembly in combination a medicament container, a wall closing one end of said container, a hollow needle within said container and having its outer pointed end disposed adjacent said wall, a member secured to said needle at a point to the rear of its outer end and said member extending adjacent and beyond said wall whereby upon a pull being exerted upon said member, said needle will pierce said wall and be projected beyond the same.
3. In a syringe assembly in combination a container closing member, a hypodermic needle disposed adjacent the same, a flexible cord-like pulling member fixedly secured to said needle and said member being slidably supported by said closing member to project said needle.
4. In a syringe assembly in combination a container closing element, a hypodermic needle disposed adjacent the same, a flexible cord-like projecting member fixedly secured to said needle, said member being slidably supported by said element and digital gripping means secured to said member at a point beyond said element.
5. In a syringe assembly in combination a container closing element, a hypodermic needle disposed adjacent the same, a flexible projecting member secured to said needle, said member being slidably supported by said element and said element being formed with a recess in its rear face against which the surfaces of the needle adjacent its rear end bear in supporting relationship as said needle is caused to slidably project by a pull exerted upon said member.
6. In a syringe assembly in combination a container closing element, a hypodermic needle disposed adjacent the same, a flexible projecting member secured to said needle, said member being slidably supported by said element, said member extending beyond its point of securing to said needle in spaced relationship to the latter and beyond said element.
7. In a syringe assembly in combination a container closing element, a hypodermic needle disposed adjacent the same, a projecting member secured to said needle, said member being slidably supported by said element and extending beyond the latter and said member being formed of flexible material.
8. In a syringe assembly in combination a stopper for a container, said stopper being formed with a recess in its rear face, a pierceable diaphragm portion defining the base of said recess, a hypodermic needle having its body projecting into said recess and with its pointed outer end adjacent said diaphragm, a flexible pulling member having a rear portion attached to the body of said needle

at a point short of said recess and said member extending in sliding relationship to said stopper and beyond the outer face of the same.

9. In a syringe assembly in combination a stopper for a container, said stopper being formed with a recess in its rear face, a pierceable diaphragm portion defining the base of said recess, a hypodermic needle having its body projecting into said recess and with its pointed outer end adjacent said diaphragm, a flexible pulling member having an offset rear portion attached to the body of said needle at a point short of said recess, said member extending in sliding relationship to said stopper and beyond the outer face of the same whereby upon a pull being exerted upon said member said needle will be projected through said diaphragm portion to extend beyond the outer face of said stopper and said offset portion bearing against the rear face of said stopper in such projected position of the parts to support the adjacent ends of said needle and member.

10. In a syringe assembly in combination a stopper for a container, said stopper being formed with a recess in its rear face, a pierceable diaphragm portion defining the base of said recess, a hypodermic needle having its body projecting into said recess and with its pointed outer end adjacent said diaphragm, a flexible pulling member having a rear portion attached to the body of said needle at a point short of said recess, said member extending in sliding relationship to said stopper and beyond the outer face of the same, a pull portion forming a part of said member beyond the outer stopper face whereby said needle may be projected through said diaphragm portion and extends beyond said stopper and means forming a part of said stopper for maintaining the latter against movement with respect to a container to which it is applied.

11. In a syringe assembly in combination a flexible container having a pierceable outer wall, a needle disposed within said container and having a pointed end disposed adjacent said wall and a pulling member extending through said wall and having its inner end attached to the inner end of said needle.

12. In a syringe assembly in combination a container for medicament, a pierceable closure disposed adjacent one end of said container, a hypodermic needle having its pointed end adjacent said closure and its body within said container, a pulling member connected with said needle within said container and extending through said closure member to a point beyond the same, a holder to support and receive said container and provided with an opening through which said member may extend and means for securing said member against movement with respect to said holder.

13. In a syringe assembly in combination a container for medicament, a pierceable closure disposed adjacent one end of said container, a hypodermic needle having its pointed end adjacent said closure and its body within said container, a pulling member connected with said needle within said container and extending through said closure member to a point beyond the same, a holder to support and receive said container and provided with an opening through which said member may extend, a piston mounted by said container, said piston being formed with a cup-shaped recess in its outer face, a plunger having a part to extend into said recess and means associated with said plunger for clamping the lips of said cup in engagement with said parts whereby to secure said piston against movement with respect to said plunger as the latter is projected and retracted.

14. In a syringe assembly in combination a container, a pierceable closure adjacent one end of said container, a hypodermic needle having its pointed end disposed adjacent said closure and its body extending into said container, a pulling member secured to the body of said

needle and extending in sliding relationship with respect to said closure and beyond the same, a stopper within said container and spaced from said closure to divide the container into compartments and a sealing element connected to said pulling member and engaging with the surfaces of said stopper to normally prevent movement of fluid from one compartment to another.

15. As an article of manufacture for use in a syringe assembly as defined in claim 1, a hollow needle having a pointed outer end, a pulling member connected to said needle to the rear of its point, a closure supporting said needle and member and coupling means supported by said closure and connectable with a piston for shifting the latter.

16. A syringe assembly including in combination a member providing a chamber for medicament, a needle disposed adjacent one end of said member, means for sealing that end of the member, a piston adjacent the opposite end of said member and flexible actuating means operatively connected to said piston and extending adjacent said one end of the member for shifting said piston with respect to said member.

17. A syringe assembly including in combination a bored barrel, a pierceable closure mounted adjacent the forward end of said barrel, a piston slidably supported within the bore of and adjacent the rear end of the barrel, a hollow needle disposed within the barrel bore with its pointed end adjacent said closure and its rear end spaced from and disposed forwardly of said piston and means extending forwardly adjacent said closure and beyond said barrel for projecting said needle through said closure.

18. A syringe assembly including in combination a bored barrel, a pierceable closure mounted adjacent the forward end of said barrel, a piston slidably supported within the bore of and adjacent the rear end of the barrel, a hollow needle disposed within the barrel bore with its pointed end adjacent said closure and its rear end spaced from and disposed forwardly of said piston, means extending forwardly adjacent said closure and beyond said barrel for projecting said needle through said closure, the inner face of said closure being formed with a recess having a diameter such that it may snugly embrace the needle and said needle throughout a zone adjacent its pointed end being disposed within said recess.

19. A syringe assembly including in combination a bored barrel, a pierceable closure mounted adjacent the forward end of said barrel, a piston slidably supported within the bore of and adjacent the rear end of the barrel, a hollow needle disposed within the barrel bore with its pointed end adjacent said closure and its rear end spaced from and disposed forwardly of said piston, a member secured to said needle adjacent the rear end of the latter and said member extending forwardly beyond said closure and in slidable relationship with respect to the same whereby a pull exerted upon said member at a point beyond said closure will cause the pointed end of said needle to penetrate said closure and project forwardly of said barrel.
